UNITED STATES PATENT OFFICE.

WILLIAM S. BIDLE, OF CLEVELAND, OHIO, ASSIGNOR TO THE W. S. BIDLE COMPANY, OF CLEVELAND, OHIO, A CORPORATION OF OHIO.

RIVET SET.

Application filed November 7, 1925. Serial No. 67,588.

My invention relates to an improvement in rivet sets, and the primary object of my invention is to provide a rivet set which is particularly constructed to permit it to be hardened by heat treatment and have greater durability and longer life than the common type of rivet sets in general use, all substantially as herein described and more concisely pointed out in the claims. Thus in the accompanying drawing, Fig. 1 is a sectional view of my improved rivet set made in two separable parts, and Fig. 2 is a side view of a common type of rivet set, of the same size, the two views permitting comparison of the shape of their respective heads and shanks. Fig. 3 is a side elevation of the main part of the rivet set without its split ring, and Fig. 4 is a horizontal cross section of the head and split ring, on line 4-4 of Fig. 1.

The common type of rivet set A, shown in Fig. 2, is made in one piece and comprises a grooved head *a* having a straight integral shank *a'* joined to the head with a short or abruptly curved fillet *a''*. The general contour and size of such rivet sets permits them to be used effectively with pneumatic tools, the shank fitting loosely within a working bore where it may be engaged repeatedly by a piston or hammer and the head being grooved to permit it to be held by a retaining clip or other device so that the rivet set may not be ejected accidentally when not held against the work. In recoiling, the shoulder or fillet portion *a''* strikes the end of the pneumatic tool and it is usually at this juncture *a''* that the rivet set develops fatigue and fractures.

My improved rivet set comprises a round straight shank 2 of the same diameter and length as the shank in the old type described so that it may be removably fitted within any standard pneumatic riveting tool in which a reciprocable piston or hammer is employed to repeatedly strike the chamfered end portion 3 of the shank. An enlarged upsetting or riveting head 4 forms an integral part of shank 2, the material involved in this head being the same in length as in the old type and consisting of all of that portion beginning with the riveting end 5 having riveting cavity 6 and including the tapering curved connecting portion 7 of lesser diameter which joins with and ter-

minates at the base end of straight shank 2. Thus the rounded riveting part 5 of the head is relatively the largest integral part of the rivet set, being correspondingly as wide vertically as annular enlargement 5' in the old type of rivet set A shown in Fig. 2 but made slightly larger in diameter to provide a flat annular seat or shoulder 8 at right angles to the straight side of a reduced section 9 of head 4. Reduced part 9 is of slightly less diameter than the grooved part 9' of the old type of rivet head *a* which comprises a narrow annular rib or enlargement *a'''* at the abrupt juncture with shank *a'*. A similar narrow annular rib or enlargement 10 forms part of head 4 in my device but it is located much nearer to the rounded riveting end 5 to provide a narrower reduced part or groove 9 compared with grooved part 9' in the old head *a*. Thence head 4 tapers upwardly on a long curve or radius 11 to produce a gradual decrease in diameter of head 4 and to avoid an abrupt junction with straight shank 2, thereby avoiding marked changes in the grain and high stress locally at the juncture of the head with the shank.

The flat annular shoulder 8 which is relatively near the upsetting end of the head seats the flat end 12 of a split ring 13 made of hardened spring steel. In that connection, I find that an abrupt change in cross section is permissible in head 4 itself providing it is located relatively near the upsetting end where the stock in the head and not the stock in the shank is involved. Thus it should be noted that shoulder 8 is formed by slightly enlarging the head and that the annular reduced part 9 is considerably larger in diameter than shank 2 and also larger than riveting cavity 6 in end 5. Ring 13 may be made of a cheaper grade of material than head 4 but it is hardened and tempered to prevent it from upsetting under recoil movements of the hammer. Ring 13 is formed internally at its lower end with an annular rib 14 which springs over enlargement 10 and fits snugly within the grooved part 9 in head 4, and an annular groove 15 formed externally of the ring provides limiting stop shoulders 16 for the spring clip or other holding device (not shown) but customarily employed to grip and hold

the rivet set in a reciprocable working position upon the pneumatic tool. Ring 13 is a detachable part of head 4, but when affixed in spring clasping connection therewith it is slightly larger in diameter externally than the solid head 5' of the one piece rivet set delineated in Fig. 2. When the ring is attached it is spaced apart from the curved part 11 of the head and stands entirely apart from and remote from shank 2. Furthermore, the flat seat 8 for the ring resists squarely, the recoil, and prevents any spreading or wedging effect from being transmitted to the split ring.

15 Head 4 is subjected to great strain and wear and obviously this part with its integral shank must in time be replaced, but split ring 13 being made of spring steel and heat treated and tempered separately from the main member may be removed from a worn riveting head and replaced on a new one by the aid of suitable tools. However, a riveting head and shank constructed according to my invention will withstand severe usage and outlast all other types of rivet sets known to me and in general use, the device having been particularly designed to resist exceptionally high fatigue stresses. In that connection it should be understood that fatigue tests have demonstrated that sudden changes of cross-section should be avoided at critical places or especially important junctures as abrupt changes of outline greatly lower the resistance of the specimen to repeated stress. High stress concentration is produced by sharp variations of cross-sections with fillets of small radius and in the case of hard and brittle steels the action of stress reversal becomes of more importance than with softer steels. Rivet sets must be hard in order to stand up under the repeated blows of the hammer and to do the work required of them, and this demands that they be left in the martensitic condition after hardening. Martensite is however brittle compared to sorbite which presents the best structure to resist fatigue, and so the use of a head of gradually diminishing cross section and a gradual merger of this head with a straight shank becomes of especial importance in a rivet set which must be left in a martensitic condition. For diverse reasons it happens that rivet sets for pneumatic hammers in general use must be made with heads of considerably larger diameter than the shank, so that in hardening a piece of steel for a rivet set which has a large head section adjacent to a very much smaller one, such as a round shank connected with a short radius fillet, as shown in Fig. 2, there are internal stresses set up in the shank at the junction on quenching, and these stresses are not completely removed by subsequent tempering. These internal stresses help to form a nucleus for has-

tening the progressive failure of the finished article when it is subjected to repeated stress as in a rivet set. Theoretically it would be best to have the steel of uniformly fine-grain throughout at the junction between the head and shank as fine-grained structures have endurance properties superior to those of coarse-grained. In the case of an abrupt change of section in a rivet set there is a well defined zone where the coarser grains of the larger or head portion meet the finer grains of the shank portion, and this inhomogeneity introduces another element of weakness at the point of stress concentration. The effect of the short radius between the shank and head on the rivet sets as made in the past sets up a localized high stress at the junction of this short radius with the reduced shank of the set, which causes the set to fail at this point long before the riveting end or cavity has been worn out in heading rivets, etc. A rivet set constructed according to my invention provides a gradually diminishing amount of metal between the upsetting end of the head and the beginning of the straight shank thereby avoiding fatigue stresses at a critical place in the tool, and where an abrupt change in cross-section is necessary or desirable, such as at grooved part 9 to produce flat seat 8, it should be placed near the point of application of the force at the forward part of the head where the area or stock is from 80% to 100% greater than that of the round shank itself and not subject to the concentration of stress as at the shank.

What I claim, is:

1. A rivet set, comprising a riveting head having an annular groove and seat relatively near the upsetting end thereof and formed with an integral round shank of lesser diameter than the grooved part of said head, said head gradually diminishing in diameter from said grooved part to said shank, and a separate recoil-resisting ring affixed to the grooved part of said head adapted to bear against said seat.

2. A rivet set, comprising a head and an integral shank of reduced diameter, said head having an external groove intermediate its outer end and its juncture with said shank, and a recoil-resisting ring having an internal rib confined within said groove and formed with spaced annular shoulders externally adapted to confine a retaining member.

3. A rivet set having a round head and an integral shank of reduced diameter, said head having an external groove annularly thereof and tapering gradually from said groove to said shank, and a split recoil-resisting ring seated within said groove in detachable connection with said head.

4. A rivet set having a round head and

an integral shank of reduced diameter, said head having a flat shoulder annularly thereof at right angles to the axis of the head and formed with a small annular enlargement 5 adjacent said shoulder, said head tapering gradually from said enlargement to said shank, and a split ring having a flat end seated upon said flat shoulder and provided with an inner rib engaging said annular enlargement and formed with an annular 10 groove externally.

In testimony whereof I affix my signature.

WILLIAM S. BIDLE.
